HOB-GRINDING MACHINE.

1,383,843.

Specification of Letters Patent. Patented July 5, 1921.

Application filed February 7, 1919. Serial No. 275,537.

To all whom it may concern:

Be it known that we, CARL G. OLSON and FRANK W. ENGLAND, citizens of the United States, residing at Chicago, in the county of Cook and State of Illinois, have invented a certain new and useful Improvement in Hob-Grinding Machines, of which the following is a specification.

Our invention relates to machine tools, and is particularly applicable to hob grinding machines and similar machines in which it is required that there be frequent relative movement between the tool and work in a radial direction,—that is, toward and from the axis of the work. In the accompanying drawings we have shown a grinding wheel acting upon the teeth of a hob. The grinding tool revolves about a stationary axis and the machine is so constructed as to move the hob toward and from the work for producing the necessary relief upon the hob. The work holder swings the hob toward and from the grinding wheel and this movement is effected by a rotating cam. Special means are provided for transmitting the throw of the cam to the work holder and advantageous means are provided for altering the throw of the work holder without changing cams. Means are also provided for reversing the position of the tool relatively to the work. In our illustrated machine, also, the grinding tool is located behind the work,—that is, on the side opposite to the operator. Furthermore, the parts are so arranged and operated that the grinding tool moves downward at the point of contact with the work, with the result that the sparks are driven downward instead of upward and it becomes safe for the operator to bring his face close enough to the acting point to scrutinize the progress of the work.

The object of our invention is to produce a machine having the foregoing characteristics and to produce the various combinations and sub-combinations by which the results may be obtained.

To explain the invention we have chosen to illustrate it in a form adapted for the grinding of hobs, and in the accompanying drawings—

Figure 1 is a front elevation partly in section of the complete machine.

Fig. 2 is an end elevation looking toward the left in Fig. 1.

Fig. 3 is a top plan view of the hob, tool, and tool holder.

Fig. 4 is an elevation of the change gears as viewed when looking in the direction of the arrow A, Fig. 1.

Fig. 5 is a view, more or less diagrammatic, showing the work holder, its support, and the cam mechanism which actuates it.

Fig. 6 is a perspective view showing some of the more essential portions of the machine, so far as our invention is concerned, and

Fig. 7 is a vertical sectional view on the line 7—7, Fig. 1.

Like numerals denote like parts throughout the several views.

In the form selected to illustrate the invention, the machine has a main frame or bed 1 on which a table 2 is longitudinally slidable. A table 3 is transversely slidable upon table 2 and carries near the rear end a post 4. A tool holding frame or tool carrier 5 is pivoted to the upper end of post 4 by means of a pin 6 or equivalent device. In said frame there is journaled a spindle 7, shown in dotted lines in Fig. 3. Said spindle is adapted to take the arbor 8 of the grinding tool 9. The spindle is driven by a pulley 10 which, in turn, is driven by a belt 11. The belt is driven by a pulley 12 journalled in a yoke 13 which is slidably mounted on frame 5 so as to enable it to move toward and from the pulley 10. A helical compression spring 14 tends to force the pulleys apart and thus keep the belt 12 tight. Pulley 12 is driven by a sheave 16 fastened to the same shaft 17 as supports the pulley 12. Power to drive the sheave is derived from a belt 18 driven from a suitable power device overhead (not shown). The hob 20, which constitutes the work in the present case, is mounted on the work arbor 21 and it will be noted that the axis of the tool arbor and spindle is inclined relatively to the axis of the work spindle. This is to compensate for the helical axis of the hob. But the pin 6 which forms a pivot for the tool carrying frame 5 is arranged approximately at right angles to the axis of the arbor 21, and consequently by throwing the frame over,—that is, rotating it about its axis, the position of the grinding wheel will be reversed, thus enabling the wheel to act upon the opposite side of the hob teeth.

The work arbor 21, above mentioned, is connected to and supported and driven by the work spindle 24, best shown in Fig. 1. Said spindle has a lead screw 25 at the outer end which works in a nut 26, supported in a cap 27 screwing onto the end of the housing 28. The housing, cap, and nut are stationary so far as longitudinal movement is concerned, and hence as the spindle rotates the work will be advanced longitudinally. In order to keep the lead screw and nut dust proof, it is desirable to place a cap 30 over the outer end of the screw. According to the present design the cap is fastened to and supported by the nut.

The work spindle and associated parts are carried at the upper end of a rocking frame which is shown in perspective in Fig. 6, and more or less diagrammatically in Fig. 5. This frame is fulcrumed upon a shaft 33 and consists chiefly of the two arms 35, 36 connected by a cross brace 37. At the upper ends the arms 35, 36 have pillow blocks 39 provided with caps 40. These blocks and caps constitute journal bearings for the rotating parts. In the bearing at the left, best shown in Fig. 1, a sleeve 42 is inserted and this encircles and supports the spindle 24. The sleeve has a collar 43 which abuts one end of the cap, and a screw collar 44 which abuts the other end of the cap and holds the sleeve against longitudinal movement. In the particular form shown, the housing 28 is fastened by screws or otherwise to the blocks 39 and cap 40 at the left, although it will be understood that the actual design of these parts may be considerably varied without varying the essential principle,—which is that spindle 24 rotates and feeds longitudinally in a rocking frame which, in rocking, produces a relative movement between the work and the tool in a direction transverse to the axis of the work.

The mechanism for rotating the spindle and at the same time permitting it to feed longitudinally includes a rotatable sleeve 46 which is journaled at one end upon the sleeve 42 and has an internal feather 47 which projects into a slot 48 formed in a collar 49 fastened to or forming an integral part of spindle 24, as shown in detail in Fig. 7. Said feather extends parallel to the spindle axis and hence drives the spindle but at the same time permits it to travel longitudinally. Sleeve 48 is driven in the present instance by a spur gear 50, driven by a pinion 51 fastened to the shaft 33, above mentioned. Said shaft is journaled in bearings 53, 53, rising from the stationary bed 1 and is driven by a pulley 54, as best shown in Fig. 1. In practice said pulley is not rigidly fastened to the shaft, but is connected to it through reversing transmission mechanism adapted to drive the shaft at a relatively slow speed forward, and relatively

high speed backward. Reversible transmissions suitable for the purpose are well known and consequently need not be here described in detail. Pulley 54 is driven by a belt 55 from a suitable overhead power device (not shown).

Now referring particularly to the mechanism which oscillates the rocking frame 35, 36, 37: A cam shaft 57 is journaled in stationary bearings 58, 58 and is driven by change gears from the shaft 33. As shown in perspective in Fig. 6 and in detail in Fig. 4, a gear wheel 60 is fastened to shaft 33, a gear wheel 61 is fastened to shaft 57, and motion is transmitted from one to the other by intermediate gears 62, 63 which rotate as a single piece and mesh respectively with the wheels 60 and 61. These intermediate gears are supported upon a stud 64 adapted to be clamped in any suitable position upon a slotted arm 65 pivoted to shaft 57. By suitably selecting the intermediate pinions 62, 63 any desired speed ratio between shafts 33 and 57 may be obtained. Although it is not essential, it is desirable to form the cam shaft in two parts 57, 57^a connected by a spring ratchet mechanism 68 shown in perspective in Fig. 6. The function of the ratchet mechanism is to permit the section 57 of the shaft to rotate backward without rotating the section 57^a backward. Fastened to the section 57^a of the cam shaft is a cam 70, the acting surface whereof is in the form of a spiral, thus forming a snail cam. Co-operating with the cam is an arm 71 pivoted upon a stationary fulcrum pin 72. The arm has a lug 74 on its underside which rests upon the cam with the result that as the cam rotates the arm 71 gradually rises and then suddenly falls. Riding upon the back or upper surface of the arm is a block 76 having a knife edge 77 for contacting the arm. The block is guided in a slot 80 arranged horizontally in the forward extension 81 of the arm 36 of the rocking frame. A screw 82, shown in side elevation in Fig. 2, controls the position of the rider block lengthwise of the extension and thus controls the amount of throw of the rocking frame. By shifting the block away from pin 72 the throw will be increased and vice versa. As a result of this construction in which an intermediate arm 71 is interposed between the cam and the rocking frame, the movement produced by the cam may be magnified or diminished.

A helical compression spring 88 rests upon the bed 1 and supports a jack screw 89 screwing vertically in the lug 90 formed at the rear end of the rear extension 91 of the rocking plane. This serves to keep the rider block 76 in close contact with arm 71, and the latter in close contact with the cam 70.

In operation, when a hob is to be ground, the parts are assembled and adjusted as

- shown in the drawings and the machine is started. The driving belt 18 causes the grinding wheel to rotate at high speed, while the belt 55 causes the work spindle 24 to rotate and simultaneously feed the hob forward in an axial direction. The cam is also caused to rotate, which produces an oscillatory movement in the rocking frame and moves the hob gradually toward and 10 suddenly away from the wheel axis. This conforms to the relief in the hob teeth and it will be understood that the parts are so geared that the cam will rotate as many times faster than the hob as there are teeth 15 in a complete circumference of the hob. The grinding wheel not only rotates in a direction to throw the sparks downward, but the wheel itself is located at the back of the machine—or at least on the side of the hob 20 away from the operator. Consequently, the operator may lean over toward the work without danger of coming into contact with the fast rotating grinding wheel. Furthermore, as the sparks are thrown downward 25 there is no danger of their being thrown into the operator's eyes when he leans over to inspect the work. In addition, gravity assists in collecting the resulting dust and grit in an exhaust duct (not shown) which 30 may be provided for conveying the same away from the machine.
- After the wheel has ground one side of all of the hob teeth, the belt 18 is thrown off the sheave 16, whereupon the tool carrying frame 5 may be turned over about its horizontal axis 6 thus causing the acting surface of the tool to present the proper angle to grind the opposite side of the teeth. The hob is brought back to starting position again, with the grinding wheel engaging the opposite side of the hob teeth, whereupon the action may be repeated and the grinding finished.
- It will be noted that the sheave or pulley 16 is so located in the tool carrier that the "on" side (shown at the right in Fig. 3) is substantially in line with the axis of the pivot which connects the tool carrier to the "tool." The advantage in this is that it 40 enables the tool carrier to be turned over to reverse position without disturbing the relation of the sheave or pulley to the belt. In other words, the belt will run on to the pulley as well with the tool carrier in one position as it will with it in the reverse position.
- Having thus described the invention what we claim as new and desire to secure by Letters Patent, is:—
1. A machine tool having a tool holder and a rocking frame, one of which oscillates about a fixed axis for producing relative movement between the tool and the work for producing relief in the work, means for rotating the work in the work holder, a rotating cam, a pivoted arm actuated by said cam, a rider carried by the aforesaid part which oscillates, for transmitting the movement of the arm to the part which oscillates, said rider being adjustable relatively to the axis of the part which oscillates. 70
  2. A machine tool having a rocking frame for swinging the work toward and from the tool for taking an eccentric cut, a cam for oscillating the rocking frame, a pivotally supported arm adapted to be oscillated about its pivot by said cam, and a rider directly coöperating with the arm and the rocking frame for transmitting the oscillatory movement of the arm to the rocking frame, said rider being adjustable toward 75 and from the axis of one of the elements with which it directly coöperates. 80
  3. A machine tool having a work holder, a tool holder adapted to present a tool to the work, and a support in which the tool holder 85 is journaled, the projected axis of the tool holder in its support passing approximately through the point of application of the tool to the work whereby the tool may be reversed and present its face at a similar angle 90 in the opposite direction.
  4. A machine tool having a tool post, a tool holder at an oblique angle to the axis of the work, a spindle journaled in the tool holder and adapted to rotate the tool, the 95 tool holder being pivoted to the post and adapted to swing about an axis lying approximately in a plane containing the axis of the spindle whereby the position of the tool carrier relatively to the work may be 100 reversed to thereby reverse the angle presented by the tool to the work.
  5. A hob grinder having a tool post, a tool carrier, a spindle journaled in said tool carrier and adapted to carry the grinding 105 wheel, and a work spindle for supporting and rotating the hob, the tool carrier holding the axis of the tool spindle at an oblique angle to the hob axis, and the tool carrier being pivoted to the tool post upon an axis 110 oblique to the axis of the tool spindle. 110
  6. A machine tool having a tool carrier, a tool spindle journaled in said carrier, a pulley for driving the tool spindle, a slide 115 slidably mounted upon the tool carrier, a drive pulley journaled upon said slide, a belt for transmitting the motion of the drive pulley to the first mentioned pulley, and a spring for yieldingly forcing the pulleys apart to thereby keep the belt tight. 120
  7. A machine tool having a tool post, a tool carrier pivoted to said post whereby the tool carrier is reversible, a tool spindle journaled in the tool carrier, and a pulley mounted upon the tool carrier and connected 125 to the tool spindle for rotating it, the "on" side of the pulley being substantially in line with the axis of the pivot connection between the tool carrier and the tool post.
  8. A hob grinder having a tool carrier, a 130

- tool spindle journaled in said carrier for rotating the grinding wheel, a work spindle for supporting the hob, means for rotating the hob spindle and simultaneously causing it to advance axially, a rocking frame where-in said work spindle is journaled, and a rotating cam adapted to rock the frame a plurality of times for every single rotation of the work spindle about its axis.
- 10 9. A hob grinder having a tool carrier, a tool spindle journaled in said carrier for rotating the grinding wheel, a work spindle for supporting the hob, means for rotating the hob spindle and simultaneously causing it to advance axially, a rocking frame where-in said work spindle is journaled, and a snail cam acting upon the rocking frame for moving the hob gradually toward the grinding wheel and suddenly away from it, the 15 revolutions of the cam per minute being a multiple of the revolutions of the work spindle per minute.
- 10 10. A hob grinder having a work spindle for rotating the hob, a rocking frame where-in said spindle is journaled, a tool carrier located at the rear of the frame, and cam mechanism in front of the tool spindle for rocking said frame to thereby move the work toward and from the tool.
- 30 11. A relieving hob grinder having a rotatable work spindle adapted to carry the hob, a post, a frame journaled in said post about an axis which, if extended or produced, will approximately pass through the 35 axis of the work spindle, a grinder spindle journaled in said frame and adapted to hold the grinder in contact with the hob at a point approximately in line with the axis of rotation of the frame, means for producing relative travel between the post and the work 40 spindle in a direction parallel to the axis of the work spindle, and means operating in timed relation with the speed of rotation of the work spindle for periodically reciprocating said frame toward and from the axis 45 of the work spindle.
12. A hob grinder having a work spindle for rotating the hob, a post, the post and the hob having a uniform relative motion parallel to the axis of the work spindle, a 50 disk-like grinder, a grinder spindle adapted to hold the side of the grinder in contact with the side of the hob teeth, the point of contact of the grinder with the hob teeth lying approximately in the same plane with 55 the axis of the work spindle and the axis of the grinding spindle, a frame in which the grinder spindle is journaled, a post upon which said frame is pivotally supported, the axis of the frame lying approximately in 60 the same plane as the axis of the work spindle and the axis of the grinder spindle, and driving means for said spindle carried by the frame and rotatable with it.

In witness whereof, we have hereunto sub- 65 scribed our names.

DISCLAIMER.

1,383,843.—*Carl G. Olson and Frank W. England, Chicago, Ill., HOB-GRINDING MACHINE.* Patent dated July 5, 1921. Disclaimer filed December 12, 1924, by the assignee, *Illinois Tool Works*.

Hereby enters this disclaimer—

“To that part of the claim in the said specification which is in the following words, to wit:

“3: A machine tool having a work holder, a tool holder adapted to present a tool to the work, and a support in which the tool holder is journaled, the projected axis of the tool holder in its support passing approximately through the point of application of the tool to the work whereby the tool may be reversed and present its face at a similar angle in the opposite direction.

“4. A machine tool having a tool post, a tool holder at an oblique angle to the axis of the work, a spindle journaled in the tool holder and adapted to rotate the tool, the tool holder being pivoted to the post and adapted to swing about an axis lying approximately in a plane containing the axis of the spindle whereby the position of the tool carrier relatively to the work may be reversed to thereby reverse the angle presented by the tool to the work.

“5: A hob grinder having a tool post, a tool carrier, a spindle journaled in said tool carrier and adapted to carry the grinding wheel, and a work spindle for supporting and rotating the hob, the tool carrier holding the axis of the tool spindle at an oblique angle to the hob axis, and the tool carrier being pivoted to the tool post upon an axis oblique to the axis of the tool spindle.

“11. A relieving hob grinder having a rotatable work spindle adapted to carry the hob, a post, a frame journaled in said post about an axis which, if extended or produced, will approximately pass through the axis of the work spindle, a grinder spindle journaled in said frame and adapted to hold the grinder in contact with the hob at a point approximately in line with the axis of rotation of the frame, means for producing relative travel between the post and the work spindle in a direction parallel to the axis of the work spindle, and means operating in timed relation with the speed of rotation of the work spindle for periodically reciprocating said frame toward and from the axis of the work spindle.

“12. A hob grinder having a work spindle for rotating the hob, a post, the post and the hob having a uniform relative motion parallel to the axis of the work spindle, a disk like grinder, a grinder spindle adapted to hold the side of the grinder in contact with the side of the hob teeth, the point of contact of the grinder with the hob teeth lying approximately in the same plane with the axis of the work spindle and the axis of the grinding spindle, a frame in which the grinder spindle is journaled, a post upon which said frame is pivotally supported, the axis of the frame lying approximately in the same plane as the axis of the work spindle and the axis of the grinder spindle, and driving means for said spindle carried by the frame and rotatable with it.”
